PORTABLE LAMP

Shirley R. Naysmith, Meriden, Conn., assignor to
 The Miller Company, Meriden, Conn., a corporation of Connecticut

Application December 6, 1945, Serial No. 633,097

4 Claims. (Cl. 240—81)

1

The present invention relates to portable lamps and is more particularly directed toward portable lamps employing a single upright lamp bulb arranged to provide an indirect lighting component, and a diffused direct lighting component and having an enclosing translucent shade.

According to the present invention the lamp bulb is associated with an enclosure extending from the region of the lamp socket up to the level of the maximum diameter portion of the bulb. This enclosure has its maximum diameter at substantially the level of the lamp filament and below this level of the lamp filament is light diffusing. Immediately above this maximum diameter portion, the enclosure is also light diffusing. This latter light diffusing portion is adapted to produce a substantial amount of transmitted light directed in regions above the horizontal so as to illuminate the upper part of the outer enclosing shade.

The accompanying drawings show, for purposes of illustrating the present invention, two embodiments in which the invention may take form, it being understood that the drawings are illustrative of the invention rather than limiting the same.

In these drawings:

Figure 1 is a vertical sectional view through one form of construction; and

Figure 2 is a vertical sectional view through another form of construction.

In Figure 1 the lamp 10 has its filament at 11 and is carried in an upwardly opening lamp socket 12 in the usual manner. Here the enclosure is made in two parts, the lower piece being a glass or plastic shade 13 while the upper piece of the enclosure 14 is in the form of a metal reflector 14. The reflector 14 carries a metal reflector 15 adapted to allow light to escape upwardly as will be obvious. An outer translucent shade 16, a generally conical shade, extends downwardly from the top of the reflector 15.

The horizontal through the lamp filament is indicated by the line 17—17 and the maximum diameter of the glass or plastic portion of the enclosure is at approximately the level of the filament. Immediately above this maximum diameter portion, the translucent part of the enclosure indicated at 18 is reentrant and is nearly horizontal. It will receive a substantial amount of light flux in the general direction of the arrow 19 falling on it, however, in all directions because of the diffuse reflection of the

2

inner surfaces of the translucent material. The light is transmitted as indicated by the circle 20 and a very substantial portion of the light is directed upwardly because of the shape of the translucent material. This upwardly directed light falls on the upper portion of the translucent shade 16 so that it is lighted up. As the shade 16 obtains all its light from light diffusely transmitted through the translucent member, the entire shade can be lighted up very evenly.

In Figure 1 the metal reflector 14 is indicated as being a specular reflector which directs the light it intercepts downwardly toward the diffusing transmitter. In constructions such as shown in Figure 1, the enclosure made up of the light transmitting and reflecting elements 13 and 14 may extend from about 20° to 30° above the horizontal 17. In the drawing the structure extends up to the 25° line.

In the arrangement shown in Figure 2, the lamp and socket are received in an enclosure 21 made up of a single piece of light transmitting material. The maximum diameter of this enclosure is approximately at the level of the light source. The upper reentrant portion 22 of the enclosure is here shown as occupying approximately 20° above the horizontal. It may occupy a region of from about 15° to 25° but cannot be brought in as close to the lamp as the metal reflector of Figure 1 because of the danger of overheating the glass or plastic employed. The reentrant portion 22 of the enclosure here acts the same as in Figure 1 and directs an adequate amount of light upwardly to illuminate the upper part of the shade.

Since it is obvious that the invention may be embodied in other forms and constructions within the scope of the claims, I wish it to be understood that the particular forms shown are but a few of these forms, and various modifications and changes being possible, I do not otherwise limit myself in any way with respect thereto.

What is claimed is:

1. A portable lamp comprising an upwardly opening lamp socket, an upright incandescent lamp in the socket having a bulb and a filament below the maximum diameter portion of the bulb, an opaque reflector extending upwardly and outwardly from adjacent the large diameter portion of the bulb to allow a cone of light in the region of zenith to escape for indirect lighting, a translucent conical shade extending downwardly from the top of the reflector to below the level of the socket, and an enclosure for the bulb below the reflector and for the socket, the enclosure having

an upwardly and outwardly flaring lower portion intercepting substantially all the downward light flux and diffusely transmitting it downwardly below the shade and toward the lower portion of the shade, and a reentrant translucent portion at approximately the elevation of the filament of the lamp intercepting generally horizontal light and transmitting and directing it toward the upper portion of the shade.

2. A lamp comprising an upwardly opening lamp socket, an incandescent lamp in the socket having a bulb and a filament below the maximum diameter portion of the bulb in the socket, an inwardly concave enclosure about the lamp and socket, the enclosure having a lower upwardly and outwardly flaring, light diffusing portion below the level of the lamp filament, and an upper portion extending inwardly from the top of the lower portion through an angle of substantially 15° to 30° and inwardly to be adjacent the maximum diameter portion of the bulb, an opaque reflector extending upwardly and outwardly from the top of the enclosure, and an outer downwardly and outwardly flaring translucent shade extending downwardly from the top of the reflector, the up-

per portion of the enclosure being at least in part homogeneous with the lower portion and similarly light diffusing to transmit light upwardly toward the upper portion of the shade.

5 3. A lamp as claimed in claim 2, wherein the entire upper portion of the enclosure is integral with the lower portion and occupies a region of substantially 15° to 20° above the horizontal.

4. A lamp as claimed in claim 2, wherein the upper part of the upper portion of the enclosure is a downwardly acting opaque reflector.
